UNITED STATES PATENT OFFICE.

EUGENE C. RICHARD, OF FLINT, MICHIGAN.

CARBURETER.

1,149,291.

Specification of Letters Patent. Patented Aug. 10, 1915.

Application filed February 12, 1912. Serial No. 677,235.

To all whom it may concern:

Be it known that I, EUGENE C. RICHARD, a citizen of the United States, residing at Flint, county of Genesee, State of Michigan, have invented a certain new and useful Improvement in Carbureters, and declare the following to be a full, clear, and exact description of the same, such as will enable others skilled in the art to which it pertains to make and use the same, reference being had to the accompanying drawings, which form a part of this specification.

My invention relates to carbureters and the object of my improvements is to provide an improved carbureter and one which shall adapt itself to the various conditions of practice without manipulation. I secure this object in the device illustrated in the accompanying drawings, in which,—

Fig. 1, is a central section in elevation of a carbureter embodying my invention. Fig. 2, is a detail sectional view, the section being taken at right angles to the section of Fig. 1 and at that portion of the carbureter which is at the back and top of the device, as shown in Fig. 1. Fig. 3, is a detail section on the line 3—3 Fig. 1.

A, A indicates the casing, as a whole, at the lower end of which is the reservoir B with an apparatus for maintaining a constant level of hydrocarbon therein.

C, is a jacket located toward the top of the casing A and adapted to receive any heating fluid to heat the mixture just before, it issues from the carbureter.

D, is the intake passage for atmospheric air and E, is the exit passage for the combustible mixture.

F, is a throttle valve, and G, is the handle by which the valve F is manipulated. The valve F and handle G are secured upon the shaft f.

H, (Fig. 2) is a pivoted disk provided with a pin h extending laterally from an arm extending upward from said disk. The pin h comes between the branches g, g of the lower forked end of the lever G.

j, is a spring holding the disk H firmly against its seat.

I, I indicates apertures through the rear wall of the casing A, A and J, indicates corresponding apertures in the disk H. Said apertures are so located that when the throttle valve F is wide open the apertures J shall register with the apertures I and admit atmospheric air into the mixing cham-

ber Z of the carbureter and when the throttle valve is closed the disk H shall close the aperture I. The air admitted through the apertures I, J passes into an annular chamber d which is divided from the jacket C by a horizontal wall c.

e, is an annular opening forming a communication between the chamber d and the mixing chamber Z. The opening e is toward the top of the chamber d and thus far the air passing into the chamber d passes upward toward and against the heated wall c of the chamber Z.

K, is an approximately cylindrical metal piece having a coaxial aperture or passage k extending through it. The piece K is located toward the lower end of the casing A concentric with said casing, its upper end shaped like the frustum of a cone extending into the air passage D and being provided with an annular valve seat R extending laterally outward from its largest diameter.

L, L are passages connecting the apertures k with the intake passage D.

M, is the delivery nozzle for hydrocarbon, the bore of which communicates with the reservoir B toward the bottom of the same, the delivery end being located in the aperture k.

N, is an annular groove around the part K toward the lower end thereof below the level of the hydrocarbon in the reservoir B. This groove is preferably connected with the intake passage or outer air by a small passage or groove cut in the outer surface of the part K, as shown, to permit the passage of air or liquid.

O, is a screw threaded plug having an aperture formed longitudinally therethrough. The plug O fits into an aperture which would form a passage between the annular groove N and the reservoir B below the level of the hydrocarbon therein. The hydrocarbon may pass through the aperture in the plug O to the groove N, and the area of the passage through said aperture may be adjusted by screwing the plug O out or in so that its inner end shall be more or less approximate the inner wall of the groove N.

P, is a vertical passage extending from the groove N upward.

Q, is a passage communicating at its lower end with the intake passage D below the valve seat R and at its upper end opening to the mixing chamber Z. The passage P opens into the passage Q.

S, is a thin walled cylinder constituting a valve, its lower end being adapted to seat against the valve seat R. The valve S is provided with a heavy annular outwardly extending flange W, which fits like a piston against the interior of the mixing chamber Z. The flange W fits loosely so that air shall not be trapped under it. Below the flange W there is a dividing wall y between the mixing chamber Z and the inlet passage D. The valve S fits so as to reciprocate easily through the dividing wall y and in the mixing chamber Z. There is a passage X opening to the outer air and to the mixing chamber Z above the valve S. This passage is controlled by a valve α held upon its seat by a spring ω . There is a tubular extension from the valve α which fits into the passage X inside of said valve.

Y, is a passage opening to the passage X just inside of the valve seat therein and to the mixing chamber Z below the flange W. While the valve α with its tubular extension practically closes the passage X against direct communication with the mixing chamber Z above the valve S when said valve is withdrawn from its seat, the passage Y communicates with the outer air through the passage X.

b , is a lug extending radially inward from the wall of the valve S where it supports a rod T which extends downward and when the valve S is on its seat R said rod fills the aperture k. The rod T is tapered toward its lower end at t so that the bounding lines of its cross section are parts of parabolas. The converging portion t of the rod T extends into the cylindrical aperture k. There is a screw threaded shank U extending upward from the rod T, its threads engaging interior threads in an aperture in the lug b. By turning the rod T its vertical position with reference to the valve S may be adjusted. V, is a nut, its threads engaging threads on the upper end and of the shank U, and its lower surface engaging against the upper surface of the lug b to hold the rod T in its adjusted position.

The operation of the above described device is as follows:—It is designed to maintain a constant vacuum in the mixing chamber Z and to control the delivery of hydrocarbon by controlling the velocity of the air passing the delivery nozzle. It is also contemplated to provide for a flow of hydrocarbon which shall be greater to the required extent when the charge of the engine is diluted to a greater extent by the products of combustion.

The weight of the valve S is adjusted to correspond to the vacuum required in the mixing chamber Z and the tension of the spring ω is such that the valve α shall open when there is such a vacuum in the mixing chamber. The passage E is connected with

the intake to an internal combustion engine. When the engine is not in operation, the valve S rests upon the seat R with practically its entire weight and approximately closes the connection between the inlet D and the mixing chamber Z. The valve S is balanced at this time so that there is no pressure tending to raise it. When the engine is started, and is moving slowly it does not draw a sufficient vacuum to displace the valve S and at this time air is drawn in through the passage Q and is supplied with hydrocarbon in said passage through the passage P. At this time but little air is drawn through the aperture k past the delivery end of the nozzle N because the rod T nearly closes the upper end of said aperture, and the vacuum is not sufficient to raise the hydrocarbon to the delivery end of said nozzle. When the engine begins to operate and attains a considerable speed a vacuum is drawn in the mixing chamber Z which draws the valve α from its seat and raises the valve S from the seat R thus opening communication directly between the intake passage D and the mixing chamber Z. The air passes through the passage X, the passage Y, and below the annular flange W to maintain atmospheric pressure on the underside of said flange to help raise the valve S. It will be noticed that a constant vacuum will now be maintained in the mixing chamber Z at all velocities of the engine and at all densities of the atmosphere and that the quantity of hydrocarbon supplied to the air drawn through the carburetor will be proportional to the quantity of air drawn through said carburetor that is to the volume and density of the same, because:—If the volume of air taken in by the engine is small the valve S will rise but a short distance, if the velocity increases, it will tend to draw a greater vacuum in the mixing chamber Z and the valve S will rise to supply air to said vacuum until it returns to its proper value; if the density of the air is greater it would require a greater difference of pressure to force the same volume through the same aperture and, consequently, a greater vacuum will be drawn in the mixing chamber Z until the valve S rises sufficiently to supply such vacuum and return it to its original volume. If the valve S rises, and in proportion to the distance it rises, the opening from the aperture k is enlarged inasmuch as a smaller portion of the rod T is at the mouth of said aperture and with the constant vacuum in the mixing chamber a proportionally large volume of air is drawn through said aperture and past the delivery end of the nozzle M and the cross section of the aperture k adjacent to the delivery end of the nozzle M remaining constant the velocity of the air passing it would be proportional to the volume of air drawn through

said aperture and therefore the quantity of hydrocarbon drawn from said nozzle would be proportional to the velocity or quantity of air passing through the aperture k , that is, to the height to which the valve S rises and therefore to the quantity of air drawn through the carbureter by the engine and to the density of such air.

What I claim is:—

- 10 1. In a carbureter, an intake passage for air, a mixing chamber, a valve located between said passage and chamber adapted to regulate the area of the opening between the same by the distance it rises from its seat, said valve being adapted to be caused to rise with a constant degree of vacuum in the mixing chamber, a small passage communicating with said intake passage, a conduit for liquid fuel opening into said passage, and an independent means for supplying the proper amount of fuel to the carbureter when said valve is lifted to its operative position.

2. In a carbureter, an intake passage for air, a mixing chamber, a valve located between the same and adapted to regulate the area of the opening between said passage and chamber by the distance it rises from its seat, said valve being adapted to be caused to rise with a constant degree of vacuum in the mixing chamber, an aperture communicating with said mixing chamber, and means whereby said aperture is closed when the throttle valve is closed and opened when the throttle valve is opened, a heating chamber in said carbureter toward the delivery end thereof, and means whereby the air passing through the aperture I is delivered to said mixing chamber toward the delivery end thereof and past a heated wall of said chamber.

3. In a carbureter, a mixing chamber, means for maintaining a practically constant vacuum therein, a passage for air leading to said mixing chamber, a second passage leading to said mixing chamber, means for delivering liquid fuel into said second passage operated only by the air passing through said second passage, and an automatic means for varying the effective area of said second passage so that said constant vacuum shall produce an increased flow of air through said second passage and thereby increase the delivery of liquid fuel.

55 4. In a carbureter, a mixing chamber, a

main air valve regulating the passage through said carbureter, said valve being provided with a lifting surface bounding in part an inclosed chamber, and a check valve controlling the opening to said inclosed chamber.

5. In a carbureter, an intake passage for air, a mixing chamber, a valve located between said passage and chamber adapted to regulate the area of the opening between the same by the distance it rises from its seat, said valve being adapted to be caused to rise by a definite degree of vacuum in the mixing chamber, said valve being provided with a lower surface forming the upper wall of an inclosed chamber, a passage communicating with said inclosed chamber and adapted to be put into communication with the outside air, a valve closing the connection between said passage and outside air resiliently held upon its seat and adapted to be withdrawn from its seat by the said degree of vacuum in the mixing chamber to put said passage into communication with the outer air.

6. In a carbureter, an intake passage for air, a mixing chamber, a valve located between said passage and chamber adapted to regulate the area of the opening between the same by the distance it rises from its seat, said valve being adapted to be caused to rise by a definite degree of vacuum in the mixing chamber, a small passage communicating with said intake passage and said mixing chamber past said valve and means for supplying hydrocarbon to said small passage, said valve being provided with a lower surface forming the upper wall of an inclosed chamber, a passage communicating with said inclosed chamber and adapted to be put into communication with the outside air, a valve closing the connection between said passage and outside air resiliently held upon its seat and adapted to be withdrawn from its seat by the degree of vacuum in the mixing chamber to put said passage into communication with the outer air.

In testimony whereof, I sign this specification in the presence of two witnesses.
